ARCHIBALD J. STRANE, OF TAMAQUA, PENNSYLVANIA, ASSIGNOR TO ATLAS POWDER COMPANY, OF WILMINGTON, DELAWARE, A CORPORATION OF DELAWARE.

FUSE-IGNITING DEVICE.

1,267,474.

Specification of Letters Patent.

Patented May 28, 1918.

Application filed March 11, 1918. Serial No. 221,699.

To all whom it may concern:

Be it known that I, ARCHIBALD J. STRANE, a citizen of the United States, residing at Tamaqua, in the county of Schuylkill and 5 State of Pennsylvania, have invented certain new and useful Improvements in Fuse-Igniting Devices, of which the following is a specification.

This invention relates to igniting devices 10 for fuses of the type used in mining and other commercial pursuits and also in certain military operations, the object of the invention being to provide a device of this character adapted to be easily and quickly 15 placed in position with reference to ordinary commercial fuse and which will serve to ignite said fuse with certainty under all conditions.

The lighting of the commonly termed 20 "safety fuse" or "black powder fuse" or fuse of similar type, is notoriously difficult—an amateur requiring as many as ten to twenty matches to one fuse while any one but a specially skilled worker will not be able to 25 make better than one lighting with two matches. Special schemes are known and used by some to give more favorable results as far as the actual igniting of the fuse is concerned but in many cases this has been 30 done at the expense of greatly increased risk to life or of having the device fail to perform its function with the result that the shot is missed. Other known devices have given some measure of satisfaction but at 35 such a greatly increased cost as to prevent their use from becoming general.

When candles are used for the purpose of lighting fuse of this nature the "spit" of one of the first fuses in a series to be ignited often blows the candle out and leaves the worker in a very dangerous situation—without light and in the presence of explosive charges the fuses of some of which have already been ignited. Ordinarily the worker takes time to relight the candle and even continues the igniting of the remaining fuses although the time, under such conditions, passes much more rapidly than the busy worker realizes, and often the first shot of the series explodes before the worker has reached a place of safety, with the result that he loses his life or is seriously injured. The same serious condition results when the lighting of the fuses is accomplished by 55 means of a separate flame and the work is

delayed abnormally, either because of the powder having fallen out of the ends of the fuses or having become damp from exposure to moist atmosphere. In these cases the obstinate fuses are re-cut and tried again and, 60 even if no greater damage is done, the order of the firing of the shots will be different than that planned by the respective lengths of fuse and desired order of igniting so that at best an inefficient "round" will result. 65

As this description proceeds it will be seen that the invention comprises a metal pin adapted to be inserted in the black powder core of a piece of commercial fuse said pin carrying a head of inflammable material 70 adapted to be readily ignited by friction, said head being of novel formation to adapt it to coact with the adjacent parts of the fuse in a novel and efficient manner.

In the accompanying drawing in which 75 like numerals designate corresponding parts, Figure 1 is a longitudinal sectional view upon a magnified scale, of a piece of fuse having the invention applied thereto and Fig. 2 is a transverse vertical section upon 80 line 2—2 of Fig. 1.

In the drawing 5 designates the outer coat or cover of the fuse, 6 the inner coat or lining of the fuse and 7 the black powder core. The improved igniting device constituting the subject of the present invention comprises a pin 8 having a pointed end 9 and a head 10. The head 10 is embedded in a pear shaped head 11 of ordinary match composition. The pin 8 is of such diameter and 90 length that it may be readily inserted, full length, into the powder core 7 and when so inserted will be held firmly in place. The coatings 5 and 6 of the fuse (which are usually water-proofed) form a bottle, as it 95 were, for the core 7. The head 10 of the pin and the pear shaped head 11 of match composition have a corking effect on the black powder core 7 to prevent its losing out and to prevent moisture from getting in. 100

The pear shape of the head 11 permits of said head being snugly embedded in the core 7 at the inner side of head 11 while the outer side thereof is just sufficiently exposed as to permit of ready ignition by friction 105 but not so exposed as to be accidentally dislodged. The composition of head 11 being homogeneous and of a readily propagating nature causes the flame from the outer portion to be instantly transmitted around the 110

metal head 10 to the inner portion. The metal head 10 then acts as a confining agent for the explosion of the inner portion of the composition 11 and causes the force of 5 this explosion to be extended in the direction of the black powder core which thus cannot escape ignition.

The composition 11 may or may not be dipped in a water proofing solution such as 10 melted paraffin. This composition may be of the "strike anywhere" type or of the "safety" type as desired—in the latter case a prepared scratcher is provided.

The provision of the head 10 causes the 15 composition 11 not to rely alone on adhesion but provides a positive mechanical grip between the composition 11 and the head 10 thus guarding against any possible dismembering of the device.

20 It is to be noted that when the igniting device is placed in position the taper of the inner portion of the head 11 acts after the manner of a wedge to expand the black powder core and adjacent parts of the fuse, 25 thus completely surrounding said part of the head 11 with an annular body of black powder lying in close contact with the head 11, entirely about the circumference of the latter.

30 In the use of this igniting device the operator will not be called upon to handle anything more complex or dangerous than a parlor match, nor more delicate than a slightly revised house pin. It provides 35 means whereby a single fuse or a plurality of fuses may be quickly, easily, economically and positively ignited by the most ordinary layman in any branch of work. It renders available a device so simple that any person 40 will be able to use it, so cheap that all can afford to use it, and so safe and efficient that all will desire to use it with the advantageous result that the many dangerous practices now existant in the handling of 45 explosive charges, will be eliminated.

It is to be understood that the invention is not limited to the use of this igniting device for the particular purpose set forth but that it may be used in any relation for 50 which its design and capabilities render it adaptable. It is also to be understood that the invention is not limited to the precise design herein shown but that it includes within its purview whatever changes fairly 55 come within the spirit of the appended claims.

Having described my invention what I claim is:

1. A device of the character described 60 comprising a pin having a point at one end, a head at the other end, and a mass of

match composition adapted to be ignited by friction and of substantially pear shape with its small end disposed inwardly to constitute a spreader for the powder in the 65 core of a fuse, said pin projecting a considerable distance beyond said mass to adapt it to project to such an extent into the core of the fuse as to hold the mass of match composition firmly against dislodgment 70 during the scraping movement necessary to ignite the mass of match composition by friction.

2. A device of the character described 75 comprising a pin having a point at one end, a head at the other end and a mass of match composition adapted to be ignited by friction, in which said head is embedded, said mass being of pear shape with its smaller portion disposed inwardly to thereby constitute a spreader portion for the powder core of a fuse, the proportions of the parts being such that when the igniting device is in position in a fuse the head of the pin lies substantially in the transverse plane 85 of the end of the fuse, said head acting as a deflector to direct the flame of the match composition inwardly toward the powder of the core of the fuse.

3. A device of the character described 90 comprising a pin having a point at one end and a head at the other end and a mass of match composition in which said head is embedded, said mass being adapted to be ignited by friction, the mass being substantially of pear shape with its smaller portion disposed inwardly, the body of the pin projecting a substantial distance beyond the mass of the match composition. 95

4. A device of the character described 100 comprising a pin having a point at one end and a head at the other, a pear shaped mass of match composition in which said head is embedded, the smaller portion of said mass being disposed inwardly and the proportion 105 of the parts being such that when the device is in use the head of the pin lies substantially in the transverse plane of the end of the fuse in which the device is inserted, said pin having a flaring part upon the under side of its head which acts as a deflector to direct the flame from the mass of match composition toward the powder constituting the core of the fuse in which the device is inserted. 110

115 In testimony whereof I affix my signature in the presence of two witnesses.
